UNITED STATES PATENT OFFICE.

JAMES H. MINER, OF MERIDIAN, MISSISSIPPI.

THEFT ALARM.

Application filed June 15, 1921. Serial No. 477,794.

To all whom it may concern:

Be it known that I, JAMES H. MINER, a citizen of the United States, and resident of Meridian, in the county of Lauderdale and State of Mississippi, have invented certain new and useful Improvements in Theft Alarms, of which the following is a specification.

My present invention relates to improvements in theft preventing alarms for movable or portable devices, and while described herein as an alarm for preventing the theft of motor vehicles, is capable of use in many situations.

The invention aims to provide a simple, economical, durable and efficient device which may be manufactured and sold as a unitary article and which may be readily applied by the purchaser to his vehicle, and which when so applied will be easily operated to render it inaudible when the vehicle is used by an authorized person, or set in sound producing condition to guard against theft.

I have also aimed to provide a device which will be free from gears or the like and of the fewest possible parts, thereby decreasing the cost of production and removing the liability of its getting out of order.

With these and other objects in view, the invention includes the novel features of construction and arrangement and combination of parts hereinafter described and particularly defined by the appended claims.

An embodiment of my invention is illustrated in the accompanying drawings, in which:

Figure 1 is an elevation of my improved alarm with the front casing removed to show operating parts, and

Fig. 2 is a view with the sounding member locked in inaudible position.

Referring by reference characters to this drawing, the numeral 1 designates a suitable box or case designed to contain the alarm parts which is adapted to be bolted to a suitable part of the motor vehicle, such for example as the dash or instrument or running board where it will be in convenient position to be operated by the driver to render it audible or inaudible.

Within the box or casing and suspended

preferably from the top thereof is a sounding member 2 which is made of some metal, 55 which, under the impact of a hard object, will give forth a loud sound, such for example, as bell metal, such sounding member in effect constituting a bell. Such hard object may take the form of a knocker of 60 any suitable material best suited for the purpose.

I prefer to use a plurality of knockers, as indicated at 3, and mount these so as to be vertically movable under the jars or vibrations of the body which occur when the vehicle, or other device by which the alarm is carried, is in motion. Preferably the knockers are suspended from the top wall of the case by sensitive helical springs 4. 70

The sounding board or bell is capable of vertical adjustment so that it can be positioned at the will of the operator so as to be just clear of the knockers or clappers, as shown in Fig. 1, or to press against the same 75 and hold the springs in compression, as shown in Fig. 2.

In the former position, any movement of the box or case will cause the knockers to oscillate vertically or move up and down, 80 and hence strike the sounding member 2 and emit the alarm.

In the latter position, however, the knockers will be pressed against the sounding board by the springs and no sound will 85 be produced.

A convenient manner of supporting the sounding board is to support it from a post 4 vertically movable through the top of the case or box, which is provided with locking means indicated conventionally at 5, by which the parts may be locked in either of the two positions desired.

Means may be provided, if desired, to prevent side swing of the knockers, in the 95 shape of partitions 6.

Having thus described my invention, what I claim is:

1. In an automatic theft alarm for motor vehicles an inclosing casing, a horizontally disposed sounding member located therein, a knocker element located in proximity to said sounding member, and a helical spring connecting said knocker element to the casing, said knocker element being normally 105 free to move vertically, relatively to the

sounding member, and locking means for holding said knocker against such relative movement.

2. In an automatic theft alarm, an elongated casing, a horizontally disposed sounding plate disposed in the lower part thereof, a plurality of helical springs disposed from the top of the casing, knocker

elements carried by the lower ends of said springs in proximity to said sounding plate, and means for moving said plate vertically to press it against said sounding element and for locking it in such position.

In testimony whereof, I affix my signature.

JAMES H. MINER.
